UNITED STATES PATENT OFFICE.

ASSAD M. BAROODY, OF RICHMOND, VIRGINIA.

BOTTLE-CAPPING MACHINE.

1,024,493.

Specification of Letters Patent.

Patented Apr. 30, 1912.

Application filed April 22, 1911. Serial No. 622,752.

To all whom it may concern:

Be it known that I, ASSAD M. BAROODY, a citizen of the United States, residing at Richmond, in the county of Henrico and State of Virginia, have invented certain new and useful Improvements in Bottle-Capping Machines, of which the following is a specification.

This invention relates to machines for capping bottles or the like, and embodies in its construction a traveling bottle carrier, a plunger mechanism for affixing the caps thereto, and means to deliver the bottles from the carrier after they are capped.

15 Means are provided for forcing the bottle upwardly in the carrier to receive the cap which is held in a holder, the caps being fed to proper position from a chute.

In the accompanying drawings—Figure 20 1 is a side elevation of the machine partly in section. Fig. 2 is an end elevation thereof partly in section. Figs. 3 and 4 are details of the cap feeding and gripping mechanism.

25 Referring specifically to the drawings, A is the base of the machine and B is the main shaft bearing or support bolted to the base.

C is an arm fastened to the support B, and at its upper end overhangs the traveling 30 carrier and supports the die O against which the top of the cap is pressed by the bottle thereunder.

F is a lever pivoted on the arm C, and connected at its upper end to a rod G which 35 works through a guide in the arm and has a spring E coiled around the same at the front end thereof. The lower end of the lever runs in a cam groove 5 in a collar on the main shaft, whereby the lever F is 40 vibrated.

N is a vertical chute connected to the pivoted hopper J by an inclined chute M, the hopper J being pivoted at L on a support K fastened to the arm C and vibrated 45 up and down by a rod 7 connected to an eccentric 6 on the main shaft, the vibration of the magazine causing the caps to feed down the chutes M and N.

H is a rod which is pressed by a spring h 50 coiled around the same, and the springs E and h act to grip a cap between the heads x at the ends of the rods G and H when said cap is advanced therebetween by the action of the feed plunger P. This plunger P 55 works in a casing at the bottom of the chute

N, and acts to advance caps from said chute to position under the die O. The plunger P is operated by a lever Q fulcrumed on a bracket R and intermittently operated by pins S which strike the lower end of the lever Q and serve to retract the plunger P. After the pins pass the lever Q the plunger is advanced by a spring 20 to feed the caps.

1 is a lever which is pivoted at one end at 4, to the arm C, and is connected at the other end by a pin 21, which extends through a slot in the lever, to the lower end of a plunger 2. The lever 1 is lifted by a cam 3 on the main shaft 22 which cam also has a crank pin 23 connected by a rod 8 to a pawl lever 10 which carries a spring pawl engaging a ratchet 24 on the shaft Z which also carries sprocket wheels Y between bearing standards 11 on one end of the base. The sprockets, shaft, and supports, are duplicated at the opposite end of the base. Chain belts U extend around these sprockets, in proper position to pass over the plunger 2, and the chains carry bucket sections T which form holders to carry the bottles, the sections being pressed toward each other by springs V, permitting the holders to be opened to facilitate putting the bottles in place and also to accommodate any slight variation in the size of the bottles.

80 W is a guide track over which the upper run of the belt passes, said guide track being supported by the arm C and having a depending guide or collar 25 in which the plunger 2 operates. The track W also supports a delivery chute X, leading to a conveyor belt 13 which passes around a wheel 12 between boards 14 to carry the bottles away. The main shaft 22 has a pulley D whereby 85 it is driven.

90 In order to support the caps in the chute N, and hold them off the plunger P until the proper time I provide a pair of levers 27 pivoted at 30 and having projections 29 which work through the wall of the chute and act as stops for the caps until the levers are moved to withdraw the projections. The levers are connected by a link 26. One lever is located in the path of a finger 25, projecting from the plunger P, and when the finger strikes said lever both levers are rocked to withdraw the projections 29 and allow the caps to drop onto the plunger, which carries the lower one forward. A spring 28 returns the levers. The plunger 95 100 105 110

advances the cap between the heads ω , and as the bottle rises the rod G is drawn back by the action of the lever F, working in the cam groove, to release the cap and permit 5 the bottle to press the same into the die.

The operation is as follows: When the main shaft is turned it revolves the cam 3 which raises the plunger 2 by means of lever 1, and the plunger rises at each stroke into 10 a holder T and against the bottom of a bottle held thereby, thereby lifting the bottle against the cap which has been advanced by the plunger P and is at that instant held with spring pressure between the plungers 15 G and H, and as the bottle is lifted it presses the cap upwardly into the die O, forcing the same onto the mouth of the bottle. Then the plunger 2 and the bottle supported thereby drop, and the carrier belt is then 20 advanced by the operation of the crank pin 23, rod 8 and pawl and ratchet 24, bringing the bottle to the mouth of the chute X down which it drops and advancing the next bottle to position over the plunger 2 which 25 then rises for the next operation. At each step movement of the belt the caps are fed from the lower end of the chute N to position under the die O by means of the plunger P which is advanced by the spring 20 after being retracted by the pin S striking the lower end of the lever Q. The hopper J is vibrated in order to feed the caps therefrom. Any suitable mechanism may be 30 used, to feed the caps in position and succession to the chute N. The bottles are placed in the holders T by hand, before said 35 holders reach the capping position. The respective movements will of course be properly timed by means of the cams to produce the operations described. 40

Having thus described my invention, what

I claim as new and desire to secure by Letters Patent is:

1. In a bottle capping machine, the combination of a traveling belt provided with 45 bottle holders and projecting pins, means to advance the belt step by step, a reciprocating plunger over which the belt passes, said plunger being movable into and out of the holders to lift a bottle therein as the holders 50 are successively registered with the plunger, a die and cap holder located in the line of movement of the bottle so lifted, a chute for caps, a plunger movable from said chute to said cap holder to successively 55 advance caps from the chute to the holder, and a lever connected to the plunger and located in position to be struck by the pins on the belt to operate the plunger.

2. In a bottle capping machine, the combination of a traveling belt provided with 60 a series of bottle holders, each holder consisting of opposite sides hinged to the belt and springs tending to press said sides together, the holders being open at the bottom, a track over which the upper run of the belt passes, the said track having an 65 opening in the bottom thereof, a reciprocating plunger working up and down through said opening and into each holder 70 as it is located thereover, and acting to lift a bottle in the holder, and a cap holder located above the carrier and in the line of movement of the bottle and adapted to apply 75 a cap to the bottle when it is lifted.

In testimony whereof, I affix my signature in presence of two witnesses.

ASSAD M. BAROODY.
